UNITED STATES PATENT OFFICE.

WALTER F. KOKEN AND ANTON J. PICHL, OF ST. LOUIS, MISSOURI.

VALVE MECHANISM FOR INTERNAL-COMBUSTION ENGINES.

1,161,222.

Specification of Letters Patent. Patented Nov. 23, 1915.

Application filed January 16, 1914. Serial No. 812,379.

To all whom it may concern:

Be it known that we, WALTER F. KOKEN and ANTON J. PICHL, citizens of the United States, residing at the city of St. Louis, State of Missouri, have invented certain new and useful Improvements in Valve Mechanisms for Internal-Combustion Engines, of which the following is a specification.

10 This invention relates to internal combustion engines of the type that comprise slide valves for controlling the inlet and exhaust of the gases to and from the cylinders.

15 The main object of our present invention is to provide a multi-cylinder, four-cycle internal combustion engine in which the slide valves and the mechanism for operating same are of novel design.

20 Other objects and desirable features of our invention will be hereinafter pointed out.

Figure 1 of the drawings is a top plan view of an internal combustion engine constructed in accordance with our invention 25 with the cover removed, so as to show the arrangement of the co-operating openings in the valve members; Fig. 2 is a longitudinal sectional view of the engine; Fig. 3 is a side elevation of an end portion of the engine, 30 showing the valve-operating mechanism; Fig. 4 is an end elevation of same; Fig. 5 is a side elevation of the other end portion of the engine; Fig. 6 is a top plan view of one end portion of the engine; Fig. 7 is a sectional view on the line 7—7, Fig. 2; Fig. 8 is a bottom plan view, on an enlarged scale, 35 of the upper eccentric; and Fig. 9 is a sectional view on the line 9—9, Fig. 8.

For the purpose of illustration, an engine 40 having four cylinders designated by the numerals 1, 2, 3, and 4 is depicted in the drawings, each cylinder having a piston 5 adapted to operate therein in the usual manner and, also, having an inlet port 6 and an exhaust port 7 preferably located in its head, which ports are arranged below the inlet and exhaust passages 8 and 9, respectively, in the cover 10, which is secured to the heads of the cylinders by bolts 11 or other 45 suitable means. The walls of the passages 8 and 9 project upwardly into a water chamber 12 within the cover 10, and the top of this chamber is closed by a plate 13, which is secured to said cover by bolts 14 or other 50 suitable means. The inlet passages 8 are separately connected with the branches of

the manifold 15, which has the usual connection with the carbureter 16, and the exhaust passages 9 are separately connected with the branches of the exhaust pipe 17. 60 The water-jacket 18, which surrounds the cylinders, is connected with the water chamber 12 in the cover 10 by means of a pipe 18' to allow the water which enters the water-jacket 18 through the water-inlet pipe 65 19 to pass into the water chamber 12, from which it discharges through the outlet pipe 20. A spark-plug 21 and a priming-valve 22 are provided for each cylinder, the spark-plugs being preferably located on one side 70 of the engine and the priming-valves being located on the opposite side.

Communication between the inlet ports 6 and the exhaust ports 7 of the cylinders and their respective inlet passages 8 and exhaust 75 passages 9 in the cover 10 is established in proper sequence by means of plates or valve members 23 which reciprocate longitudinally in superimposed relation upon the heads of the cylinders in a longitudinal valve-chamber or groove 24 in the bottom of the cover 10. In the case of a four cylinder engine as illustrated in the drawings, two plates 23 are preferably employed, the lower plate 23 resting upon the heads of the cylinders and 80 being provided with an opening 25 for communicating alternately with the inlet port 6 and the exhaust port 7 of the cylinder 1, openings 26 and 27 for communicating separately with the inlet port 6 and the exhaust 85 port 7 of the cylinder 2, openings 28 and 29 for communicating separately with the inlet port 6 and the exhaust port 7 of the cylinder 3, and an opening 30 for communicating alternately with the inlet 90 port 6 and the exhaust port 7 of the cylinder 4, and the upper plate 23 resting upon the lower plate and being provided with an opening 31 for communicating alternately with the inlet passage 8 and the exhaust 95 passage 9 above the cylinder 1, openings 32 and 33 for communicating separately with the inlet passage 8 and the exhaust passage 9 above the cylinder 2, openings 34 and 35 for communicating separately with the inlet passage 8 and the exhaust 100 passage 9 above the cylinder 3, and an opening 36 for communicating alternately with the inlet passage 8 and the exhaust passage 9 above the cylinder 4 at the proper time. 105

Each plate or valve member 23 extends beyond one end of the cover 10, and is op-

eratively connected with an eccentric 37 on an operating shaft 38 by means of an eccentric-strap 39 and an eccentric-rod 40, which is pivotally attached at 41 to the 5 outer end of said plate, it being, of course, understood that an eccentric 37, an eccentric-strap 39, and an eccentric-rod 40 are provided for each plate 23. The operating shaft 38 is preferably arranged to occupy 10 approximately an upright position, and bears a spiral gear-wheel 42, which meshes with a spiral pinion 43 on the crank-shaft 44, being journaled in a bracket 45 or a plurality of such brackets, which may be 15 bolted or otherwise secured to the cylinder casing, and, also, in a toe-bearing 46 in a bracket 47, which may be bolted or otherwise secured to the crank-casing. The gear-wheel 42 on the valve operating shaft is 20 preferably double the size of the pinion 43 on the crank-shaft 44, so that the operating shaft makes one complete revolution to two complete revolutions of the crank-shaft and thereby causes the eccentric 37 to effect a 25 complete reciprocation of each plate 23. In order to afford a means for adjusting the eccentrics 37 upon the operating shaft 38 so as to compensate for any lost motion incident to the spiral gearing becoming 30 worn, each eccentric 37 is provided with a boss or lug 48 having teeth 49 in its face, which teeth are preferably disposed radially to the axis of the operating shaft. The lower eccentric 37 is preferably secured 35 to the operating shaft 38 by a set-screw 50 or a plurality of such set-screws or other suitable means, and has a boss 48 on its upper face, so that the teeth 49 of said boss interlock with the teeth 49 of the boss 48 40 on the lower face of the upper eccentric 37, which is revolvably mounted on the operating shaft, the upper end portion of the latter being screw-threaded to receive a nut 51 by means of which the teeth 49 of the 45 boss 48 on the upper eccentric 37 is held in interlocking engagement with the teeth 49 of the boss 48 on the lower eccentric, so that both eccentrics will rotate with the operating shaft, when the nut is tightened, and the upper eccentric can be adjusted with 50 respect to the lower eccentric when said nut is loosened sufficiently to allow the upper eccentric to be raised out of interlocking engagement with the lower eccentric. Each eccentric-rod 40 may consist of 55 two parts which are connected by a turn-buckle 52, and by this arrangement the plates 23 may be adjusted with respect to their respective operating eccentrics 37.

60 In order to lubricate the plates 23, the top of the cylinder heads and the grooves 24 in the bottom of the cover 10 are arranged to slope transversely so that the plates incline transversely, and said plates 65 are provided with transverse grooves 53 so

that the same will be thoroughly lubricated by the lubricant which flows through a pipe 54 or a plurality of such pipes into the high side of the groove 24, said pipe or pipes 54 being connected with an oil-distributing receptacle 55, to which the lubricant is forced through a pipe 56, which, leads from the centrifugal pump 57. The latter is operatively mounted upon the operating shaft 38 so as to be driven thereby 75 and is supported by a bracket 58 which may be bolted or otherwise secured to the crank-casing, said pump being connected with an oil-supply receptacle (not shown) by means of a pipe 59. A pipe 60 may be connected with the low side of the groove 24 in the bottom of the cover 10, so as to drain the surplus of oil from said groove, and may be arranged to discharge the oil into the crank-casing or elsewhere. In case the 80 engine is used to drive an automobile or the like, a pipe 61 or a plurality of such pipes may lead from the oil-distributing receptacle 55 to any part or parts of the machine requiring lubrication.

90 A centrifugal water-circulating pump 62 is operatively mounted upon the operating shaft 38, so as to be driven thereby and has its outlet connected with the inlet pipe 19 of the water-jacket 18, and its inlet connected with a pipe 63 which is connected with the radiator (not shown), it being, of course, understood that the outlet pipe 20 of the water chamber 12 is, also, connected with the radiator.

95 The operation of the engine is as follows: Referring to Fig. 2, it will be seen that the plates 23 occupy such positions that same close the communication between the inlet and exhaust ports 6 and 7 of the cylinders and their respective inlet and exhaust passages 8 and 9 in the cover 10, the pistons 5 within the cylinders 1 and 4 being at the limit of their upward stroke and the pistons 5 within the cylinders 2 and 3 being at the limit of their downward stroke, and the opening 25 in the lower plate 23 and the opening 31 in the upper plate 23 being in position ready to establish communication 105 between the inlet port 6 of the cylinder 1 and its inlet passage 8 in the cover 10 and the opening 29 in the lower plate 23 and the opening 35 in the upper plate 23 being in position ready to establish communication 110 between the exhaust port 7 of the cylinder 3 and its exhaust passage 9 in the cover 10 upon the next movement of the plates 23. It will also be noted that the ports in some of the cylinders are of different dimensions 115 than the ports in the other cylinders; that certain of the co-operating openings in the valve members are of different size than the other co-operating openings in said members; and that a single pair of co-operating 120 openings in the end portions of the valve 125

members control both the inlet and exhaust ports of the two end cylinders 1 and 4. By forming the ports in the cylinders and the coöperating openings in the valve members in this manner it is possible to accurately control the inlet and exhaust of the gases to and from all of the cylinders in proper sequence with two reciprocating valve members.

10 The crank-shaft 44 rotates in the direction indicated by the arrow, Fig. 4, and thereby drives the operating shaft 38 counter-clockwise, Fig. 6, through the medium of the valve spiral gearing. While the crank-shaft 15 is rotated through the particular 180 degrees necessary to effect a complete charging or suction stroke of the piston 5 within the cylinder 1, a complete compression stroke of the piston 5 within the cylinder 2, a complete exhausting stroke of the piston 5 within the cylinder 3, and a complete power or firing stroke of the piston 5 within the cylinder 4, the lower plate 23 moves to the limit of its travel toward the left and then moves toward the right and the upper plate 23 moves to the limit of its travel toward the left, whereby the opening 25 in the lower plate 23 and the opening 31 in the upper plate 23 open and close communication between the inlet port 6 of cylinder 1 and its inlet passage 8 in the cover 10, and the opening 29 in the lower plate 23 and the opening 35 in the upper plate 23 open and close communication between the exhaust port 7 of the cylinder 3 and its exhaust passage 9 in the cover 10. While the crank-shaft is rotated through the next 180 degrees, the piston 5 within the cylinder 1 makes a complete compression stroke, the piston 5 within the cylinder 2 makes a complete power or firing stroke, the piston 5 within the cylinder 3 makes a complete charging or suction stroke, and the piston 5 within the cylinder 4 makes a complete exhausting stroke, the lower plate 45 moves farther toward the right and the upper plate 23, also, moves toward the right, whereby the opening 28 in the lower plate 23 and the opening 34 in the upper plate 23 open and close communication between the inlet port 6 of the cylinder 3 and its inlet passage 8 in the cover 10, and the opening 30 in the lower plate 23 and the opening 36 in the upper plate 23 open and close communication between the exhaust port 7 of the cylinder 4 and its exhaust passage 9 in the cover 10. During the next 180 degrees of rotary movement of the crank-shaft 44, the piston 5 within the cylinder 1 makes a complete power or firing stroke, the piston 5 within the cylinder 2 makes a complete exhausting stroke, the piston 5 within the cylinder 3 makes a complete compression stroke, and the piston 5 within the cylinder 4 makes a complete charging or suction stroke, the lower plate 50 moves to the limit of its

travel toward the right and then moves toward the left, and the upper plate 23 moves to the limit of its travel toward the right, whereby the opening 30 in the lower plate 23 and the opening 36 in the upper plate 23 open and close communication between the inlet port 6 of the cylinder 4 and its inlet passage 8 in the cover 10, and the opening 27 in the lower plate 23 and the opening 33 in the upper plate 23 open and close communication between the exhaust port 7 of the cylinder 2 and its exhaust passage 9 in the cover 10. While the crank-shaft is rotated through the next or last 180 degrees necessary to complete a cycle in each cylinder, the piston 5 within the cylinder 1 makes a complete exhausting stroke, the piston 5 within the cylinder 2 makes a complete charging or suction stroke, the piston 5 within the cylinder 3 makes a complete power or firing stroke, and the piston 5 within the cylinder 4 makes a complete compression stroke, the plates 23 move toward the left to their normal positions, whereby the opening 26 in the lower plate 23 and the opening 32 in the upper plate 23 open and close communication between the inlet port 6 of the cylinder 2 and its inlet passage 8 in the cover 10, and the opening 25 in the lower plate 23 and the opening 31 in the upper plate 23 open and close communication between the exhaust port 7 of the cylinder 1 and its exhaust passage 9 in the cover 10.

From the foregoing it will be seen that the engine herein illustrated is so designed that the exhaust ports of the respective cylinders are closed on dead center at the upward stroke of the piston and are opened before dead center on the downward stroke of the piston, and that the inlet ports are opened on dead center at the upward stroke of the piston and are closed after dead center on the downward stroke of the piston. It will be understood, however, that whenever communication between an inlet port 6 of a cylinder and its respective inlet passage 8 in the cover and, also, between an exhaust port 7 of another cylinder and its respective exhaust passage 9 in the cover 10 is opened and closed as hereinabove described, the plates 23 prevent communication between the other inlet and exhaust ports 6 and 7 and their respective inlet and exhaust passages 8 and 9 in the cover 10.

While, for the purpose of illustration, the preferred embodiment of the present invention is depicted in the drawings, it should be understood that various changes in the details of construction and arrangement of parts and, also, substitutions may be made without departing from the nature and spirit of the present invention.

We claim:

1. A multi-cylinder, four-cycle internal combustion engine, each cylinder of which

is provided with an inlet port and an exhaust port, and a pair of reciprocating valve members arranged in sliding engagement with each other and provided with coöperating openings that coöperate with the ports in the cylinders to control the inlet and exhaust of the gases to and from all of the cylinders, the ports in some of the cylinders being of different size from the ports in the remaining cylinders.

2. A multi-cylinder, four-cycle internal combustion engine, each cylinder of which is provided with an inlet port and an exhaust port, and a pair of reciprocating valve members arranged in sliding engagement with each other and provided with coöperating openings that coöperate with the ports in the cylinders to control the inlet and exhaust of the gases to and from all of the cylinders, certain of the coöperating openings of said valve members being of different size from the remaining coöperating openings in said members.

3. A multi-cylinder, four-cycle internal combustion engine, each cylinder of which is provided with an inlet port and an exhaust port, and a pair of reciprocating valve members arranged in sliding engagement with each other and provided with coöperating openings that coöperate with the ports in the cylinders to control the inlet and exhaust of the gases to and from all of the cylinders, the ports in some of said cylinders being of different size from the ports in the remaining cylinders and certain of the coöperating openings in said valve members being of different size from the remaining coöperating openings in said members.

In testimony whereof we hereunto affix our signatures in the presence of two witnesses.

WALTER F. KOKEN.
ANTON J. PICHL.
